STARTER FOR INTERNAL-COMBUSTION ENGINES

George K. Smith, Butler, Pa.; Ethel Smith Shoemaker executrix of said George K. Smith, deceased

Application January 26, 1944, Serial No. 519,697

6 Claims. (Cl. 123—185)

The primary object of this invention is the provision for a manually operated starter as an integral part of an internal combustion engine, such as is used on small airplanes.

Another object is to provide a starter in the rear of the motor to eliminate the change of the center of gravity as occurs when such devices are mounted on the front of the motor.

Another object is to provide a manually operated starter for internal combustion engines, being a unit extremely simple, compact in form, and manufactured cheaply.

Another object is to eliminate the wind resistance caused by starters when mounted on the front of the motor.

Another object is to provide a starter which is wholly enclosed within a part of the motor casing.

This invention consists essentially of a clutch applied to the crank shaft, preferably in the rear of the motor, as will be more fully described in the following specification and shown in the accompanying drawing, in which:

Fig. 1 is a view of the device looking toward the motor showing one half of the cover removed.

Fig. 2 is a cross section taken on line 2—2 of Fig. 1.

Fig. 3 is a vertical section on line 3—3 of Fig. 2.

Fig. 4 is a vertical section on line 4—4 of Fig. 1.

Fig. 5 illustrates a modification.

Fig. 6 is a cross section on line 5—5 of Fig. 5.

As shown in the drawing, I have designated generally a standard type of an internal combustion motor 10 in which a crank shaft 11 is rotatable.

My present unit can be assembled, adjusted, and enclosed after the motor is assembled, and readjustment and repairs can be quickly made without disassembling or removing the motor.

The numeral 10 indicates generally a motor casing in which a crank shaft 11 is journaled. On the casing 10 is a housing 12 surrounding the starter and a cover plate 13 is secured on the housing 12 by bolts 14. Within the housing 12 and revolvably mounted on the crank shaft 11 is a clutch ring 15 which is provided with an L-shaped opening 16 extending from the crank shaft outwardly and substantially in line with the center of the crank shaft. Residing within a portion of the opening 16 is a roller-gripping member 17 which is adapted to contact the shaft 11. Also fitted within the outward portion of the opening 16 is a wedge member 18 having the tapered side thereof in contact with the roller 17 and adapted to move back and forth across the roller diametrically in relation thereto.

The portion of the L-shaped opening 16, in which the gripping roller 17 resides, is of a greater width than the diameter of the roller 17 which provides a space 19. In this space the roller 17 can move back and forth on the circumference of the shaft 11. The portion of the opening 16, in which the wedge member 18 resides, is of a greater width than the width of the member 18 which also provides a space 20. A small coiled spring 21 is contained within the clutch ring 15, one end of which abuts the wedge member 18 to maintain the wedge member in a forward or normal position as shown in Fig. 1.

In order to hold the roller 17 at its farthest position within the space 16, an abutting pin member 22 and a small coiled spring 23 associated therewith are contained within the clutch ring 15. The roller 17 is thus held in axial alignment with the crank shaft 11 but may roller on the bearing surface of the crank shaft when the crank shaft is rotated in a clock-wise manner.

The roller 17 and the wedge member 18 are positioned within the clutch ring 15 so that their respective end portions 24 and 25 extend beyond the sides of the clutch ring 15.

Within the motor casing 10 is an arcuate chamber 26 and in the cover plate 13 is a corresponding chamber 27. At the end of the arcuate chamber 26 are stops or abutment members 28 and 29. The cover plate chamber 27 has corresponding and equally spaced stops or abutment members 28 and 29. The abutment stops within the chambers engage with the ends 24 and 25 to limit the rotation of the clutch ring 15. The arc of the chamber and abutting stops at the ends thereof determine the duration of engagement of the gripping roller and the crank shaft.

A portion of the periphery of the clutch ring is provided with teeth 32 and teeth 33 in a slideable member 34 are arranged to engage therewith and have a sliding movement within the housing 12.

A coiled spring 35 is partly housed within the slideable member 34 and its outward end is mounted on the motor casing 10 in any suitable manner required (not shown).

In Fig. 1 the starter is shown in a normal or inoperative position, and the outer ends 24 of the gripping roller 17 abut the stop members 29, compressing the spring 23 until the roller 17 abuts the upper edge of the L-shaped opening 16, leaving a space 19 between the lower edge of the roller 17 and the L-shaped opening 16 (as shown in Fig. 1; spring shown in Fig. 3), the wedge member 18 being impelled by a spring 21 until the thin por-

tion of the wedge member 18 abuts the upper edge of the L-shaped opening 16, leaving a space 20 between the lower edge of the wedge member and the L-shaped opening 16, in which position the roller 17 moves into a larger part of the opening 16 and such opening or chamber formed thereby, in conjunction with the wedge member 18, is such that when the roller 17 has reached its extreme position, the housing space therefore will be too great for the roller 17 to exert any gripping or binding contact between the roller member 17 and the crank shaft 11.

As the clutch ring 15 rotates in a clockwise direction, the roller ends 24 leave the abutting stops 29 and the spring 23 impels the roller 17 into the smallest part of the opening 16 formed thereby, in conjunction with the thicker portion of the wedge member 18, bringing the roller 17 into locking engagement with the crank shaft 11, revolving the shaft in a clockwise direction until the projection ends 25 of the wedge member 18 come into contact with the stops 28 (as shown in Fig. 3), compressing the spring 21, retarding the wedge member 18 until the lower edge thereof abuts the edge of the L-shaped opening (as shown in Fig. 3), removing the space 20 from the bottom to the top of the wedge member 18, thereby increasing the chamber or housing space; therefore the space will be too great for roller 17 to exert any gripping action between the wedge member 18 and the crank shaft 11; therefore the said shaft may revolve freely in a clockwise direction and the coiled spring 35 through member 34 will return the clutch ring 15 to its normal position as previously recited; therefore the collar then rotates counterclockwise, the rolls 17 will be rotated in a reverse direction in respect to the rotation when the clutch ring is driven in a clockwise direction and in such circumstances there will be no tendency for the roller 17 to grip the crank shaft 11; therefore in the normal rotation of the crank shaft, the gripping roller will have a free movement therein.

Referring now to Figs. 5 and 6, in the modification I employ a return spring 38 wound around the clutch ring 15, one end thereof being anchored to the clutch ring 15 by a hook member 39 and the opposite end thereof being secured by a stud 40 on the motor casing 10. A cable 41 is wound in a groove 42 on the clutch ring 15 and one end thereof is secured to the clutch ring 15 and the other end is used for operating the starter which may be conveniently run in any angle or direction to suit the different arrangements on different types and models of planes. The operation is the same in effect as the first described construction.

While I have necessarily shown and described the preferred embodiment of my invention somewhat in detail, it is to be understood that I may vary the size, shape, and arrangement of parts within wide limits without departing from the spirit of the invention.

I claim:

1. In a manually operated starter for internal combustion engines having an inclosed crank shaft, the combination of a starter housing on the said inclosure, a clutch member on the rear of said shaft within the said housing, an L-shaped opening therein, a clutch roller within said opening, a tapered member slidably mounted therein and arranged to move across the clutch roller and arranged to operatively engage the

crank shaft, and means within the housing for limiting the duration of engagement therewith.

2. In a manually operated starter for internal combustion engines having an inclosed crank shaft, the combination of a starter housing on the said inclosure, a clutch member on the rear of said shaft within the said housing, an L-shaped opening therein, a roller member in said opening, a tapered non-rotatable movable within the chamber across the said roller diametrically therewith to urge the said roller into rotating contact with the crank shaft, means for moving the tapered member, means for disengaging the roller from gripping contact with the said shaft, and means within the housing for limiting the duration of engagement therewith.

3. A manually operated starter for internal combustion engines having an inclosed crank shaft, the combination of a starter housing on the said inclosure, a clutch member on the rear of the said shaft within the said housing, a shaped opening within said clutch member, a roller within the said opening having ends protruding beyond the side of the clutch member, a tapered non-rotatable member mounted within the said opening and ends protruding beyond the sides of the clutch member as means co-acting with the means within the housing for limiting the duration therewith, and resilient means to return the clutch member to an inactive position.

4. A manually operated starter for internal combustion engines having an inclosed crank shaft, the combination of a starter housing on the said inclosure, a clutch member on the rear of said shaft within the said housing, said clutch member having a tooth portion thereon, a slideable member having a tooth portion slidably mounted in the said housing and arranged to engage the tooth portion on the clutch member for the rocking thereof, said clutch member provided with gripping means and arranged to engage the crank shaft when the rotatable member is moved in one direction and arranged to travel idly over the crank shaft when it is moved in an opposite direction to a non-gripping position, and including resilient means for returning the clutch member to an inactive position.

5. A manually operated starter for internal combustion engines having an inclosed crank shaft, the combination of a starter housing on the said inclosure, a clutch member on the rear of said shaft within the said housing, a shaped opening therein, a clutch roller and a slideable member therein, resilient means associated with the said roller as means to normally move said roll into contact with said shaft, and resilient means associated with the tapered member to normally move the said member, and members within the housing arranged to disengage the gripping contact of the said roller.

6. A manually operated starter for internal combustion engines having an inclosed crank shaft, the combination of a starter housing on the said inclosure, a clutch member on the rear of said shaft within the said housing, means associated within the clutch member for rocking the said member, a chamber within the clutch member, means within the clutch member for gripping the said crank, resilient means for holding the gripping means in gripping contact, and resilient means to return the clutch member to an inactive position.

GEORGE K. SMITH.
